UNITED STATES PATENT OFFICE.

RODNEY G. RICHARDSON, OF CHICAGO, AND JOHN I. BELLAMY, OF BROOKFIELD, ILLINOIS, ASSIGNEES, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed February 25, 1924, Serial No. 694,842. Renewed January 16, 1929.

The present invention relates to automatic telephone systems in general, but is concerned more particularly with multi-office automatic systems of the type in which so-called "directors" are used to register, translate and retransmit telephone numbers; and the object, broadly stated, is the production of a new and improved telephone system of the foregoing character.

10 A feature of the present invention is a new and improved arrangement for cutting off a director automatically at the end of the transmission of a telephone number, as to which feature the present case may be considered as an improvement on the copending application of Nelson, Serial No. 573,175, filed July 6, 1922. In this prior case the directors are designed to receive two office digits and then to receive a subscriber's number 15 consisting of a fixed number of digits, after which they are automatically cut off. The number of digits may vary between the different offices, but for any one office the number of digits in the subscriber's number must 20 always be the same because the cut-off in each director is controlled locally by the advance of a sequence switch to a definite switching position. This makes it impossible to vary the number of digits in the telephone numbers except between complete 25 offices, as stated, which sometimes is a serious objection. Accordingly, it is one object of the present invention to provide new and improved circuit arrangements whereby the 30 director may be switched through automatically at a plurality of sequence switch positions, and independent of the total number of digits transmitted.

More specifically, the present invention 40 provides circuit arrangements whereby the switching through of the director is controlled revertively from the switch train employed in setting up a connection. The applicants are aware of the fact that such a revertive control may be accomplished in any 45 one of a number of ways, but have chosen to illustrate the invention in connection with a system in which the revertive control is accomplished according to the direction of 50 current flow in the calling loop. Two embodiments of this arrangement are shown. According to the preferred embodiment, a polarized relay in the director responds to a reversal of the trunk conductors when a con-

nector is seized and connects up two counting relays. One of these counting relays is operated locally when the tens digit is transmitted to the connector and the other counting relay operates locally at the end of the units digit. When the second counting relay 60 operates, the director is cut off from the connection and is freed in the usual manner.

According to the desirable modification of the above mentioned scheme, the trunk circuits are straight throughout the system and, 65 when a number is called containing the maximum number of digits, the director cuts itself off automatically upon the retransmission of the last digit, due to the arrival of the sequence switch at the switching position. 70 In order to cut off the director at the proper time when a number is called containing a smaller number of digits, the connector switch used for this latter number contains circuit arrangements for giving a momentary reversal of battery at the end of the units digit. This momentary reversal of battery brings about a momentary operation of the polarized relay in the director which relay now operates without the assistance of counting relays 75 to cut off and free the director at once.

Another feature of the invention relates to arrangements whereby the intermediate distributing frames, which are used to facilitate changing the office codes, are greatly 80 reduced in number. In prior systems of this character each director had its own individual intermediate distributing frame, but according to the present invention one frame is made to serve for a plurality of directors. 90 As a part of this improvement the office registers, each of which was formerly associated physically with the corresponding director, are now all mounted together side by side on shelves like ordinary Strowger switches and 95 the banks are multiplied together in the ordinary way. This conforms more nearly to standard practice and reduces the size and complexity of the director unit itself.

In addition to the objects pointed out hereinbefore, there are a great many improvements mainly incidental to the carrying out of the main objects cited and which, together with the foregoing, will appear fully hereinafter.

Referring now to the accompanying drawings comprising Figs. 1-8, inclusive, Figs. 1-6, inclusive, show by means of the usual

circuit diagrams a sufficient amount of apparatus, in a telephone system embodying the common intermediate distributing frame and the preferred arrangement for revertively controlling the cut off of the director, to enable the operation of the system to be understood; Fig. 7 is a table showing the combinations in which the relays *a*, *b*, *c*, and *d*, Fig. 5, must be operated; Fig. 8 shows a desirable modification of the scheme for revertively controlling the cut off of the director; and Fig. 9 shows the holding circuit HC which is employed in certain trunk lines when the alternate director cut off arrangement is used.

The line of the automatic substation A, Fig. 1, terminates at the exchange in the line switch C. The line switch C has access to a number of trunk circuits such as TC, each 20 of which is individual to a selector such as D. There is a secondary switch SS associated with each trunk circuit and the secondary switch SS has access to a number of directors, one of which is shown in Figs. 3-6, inclusive. A connection may be extended—under the control of the director shown—from the line of substation A through the selector D, the selector E, the repeater F, Fig. 2, the selector G, the repeater F', the selector I, the 30 selector J, and the connector K to the line of substation A'.

The substations A and A' are of the usual automatic type and each has the usual talking, signalling, and switch controlling instrumentalities.

The line switch C, Fig. 1, is mechanically of the well known rotary type in which the wipers have no normal position and move in a forward direction only. The line switch C' is similar to the line switch C. The secondary switch SS is also similar mechanically to the line switch C.

The selector D is a two motion vertical and rotary switch of the well known type and has its bank contacts arranged in horizontal rows or levels. The selectors, E, G, I, and J and the connector K are of the same type of switch mechanically.

The repeater F is an automatic repeater of a well known type and is provided to furnish talking battery to the calling subscriber from the local exchange and in order to avoid the necessity of providing three conductors in the inter-office trunk line. The repeater F' 55 is assumed to be identical with the repeater F.

The complete director illustrated in Figs. 3-6, inclusive, comprises essentially two sequence switches S and S', Fig. 3, a sender switch S², Fig. 4, and four digit registers DR-1-DR-4, inclusive, which with the necessary relays are all assembled together or otherwise physically associated for convenience in wiring, as for example by being mounted on an individual panel or rack, and 65 an office register OR, Fig. 5, which as men-

tioned before is separated physically from the associated director and is mounted on a shelf along with the office registers associated with the other directors, or a plurality of them at least.

The sequence switch S, Fig. 3, is mechanically a simple switch having the wipers 206 and 207, which are rotated in a forward direction by the stepping magnet 204 and which are restored to normal upon the energization 70 of release magnet 205, whose circuit is controlled through the off normal contacts 216. The digit registers DR-1-DR-4, inclusive, Fig. 6, are similar to the sequence switch S.

The sequence switch S' is mechanically 80 similar to the line switches C and C' and to the secondary switch SS, and its wipers are moved in a forward direction only by the stepping magnet 208 and are advanced to their normal position by the operation of the 85 same stepping magnet. The wipers of the sequence switch S' are advanced upon the backward stroke of the stepping magnet 208 rather than upon the forward stroke of the 90 said stepping magnet. The sender switch S², Fig. 4, is similar to the mechanism of the sequence switch S'.

The office register OR, Fig. 5, is a two motion vertical and rotary switch similar to the selector D. However, the switch OR has two 95 rotary magnets and may be operated in a rotary movement by long steps and by short steps as will be pointed out fully hereinafter.

The intermediate distributing frame IDF, Fig. 5, instead of being individual to one director, is common to a plurality of directors, the banks of the office registers of such plurality of directors being multiplied together and connected by cable to one side of the 100 frame.

Throughout the drawings the relays which are slow acting are indicated by a shaded portion on the lower end of the core or else by a solid black portion on the upper end of the core. The former indicates that the 105 relay is slow to fall back after its circuit is opened, but that it is not appreciably slow to pull up owing to the fact that the copper collar is placed on the heel end of the core rather than upon the armature end, and the armature is accordingly attracted by means of the lines of force which by-pass the copper collar and reach the heel piece through the air. The relays, such as line relay 6 of the line switch C, which have the black upper portion are both slow to pull up and slow to fall back, being slow to pull up on account of the fact that the copper collar is placed on the armature end of the core between the winding and the armature itself, in which case the lines of force must first penetrate the copper collar before they can reach the 115 armature.

The apparatus having been described more or less in general, the detailed description of 120

the operation will now be given. For this purpose it will be assumed that the subscriber at substation A, Fig. 1, desires to converse with the subscriber at substation A', Fig. 2. 5 For the purpose of illustration it will be assumed that the number of the subscriber at substation A', as listed in the directory, is 33-1234, the first two digits 33 designating the desired office, and the remaining four 10 digits 1234 designating the particular substation in the desired office. It is understood that ordinarily the first two digits 33 represent the first two letters of an office name and are accordingly listed in the directory as letters 15 instead of digits. This, however, has nothing particular to do with the invention and need not be considered further herein.

Assuming now that the subscriber at substation A removes his receiver, line relay 6 20 energizes over line conductors 2 and 3 in series and places ground on private normal conductor 4 at armature 16, thereby making the calling line busy to the connector switches having access to it and closing a circuit for 25 switching relay 5 and stepping magnet 7 in series. Line relay 6 also connects test wiper 9 to the junction of relay 5 and stepping magnet 7 at armature 17. Assuming that the trunk terminating in the bank contacts with 30 which the wipers 8-11, inclusive, are in engagement is idle, this latter operation of line relay 6 is of no utility at this time and switching relay 5 energizes immediately in series with stepping magnet 7, seizing the trunk. 35 In the present case, however, it will be assumed that the trunk upon which the wipers are standing is busy, in which case test wiper 9 is in engagement with a grounded bank contact, and the ground potential extended to the junction of switching relay 5 and stepping magnet 7 short circuits the former and 40 operates the latter and the wipers of the line switch are advanced step by step in search of an idle trunk, owing to the buzzer-like action of stepping magnet 7 which interrupts its own circuit.

When an idle trunk is reached, which trunk, it will be assumed, is the one comprising conductors 21-24, inclusive, switching 45 relay 5, being no longer short circuited, energizes in series with stepping magnet 7. Stepping magnet 7, however, does not energize at this time on account of the high resistance of switching relay 5. Upon energizing, switching relay 5 prepares a circuit for the magnet 50 18 of the meter M at armature 14; opens the test circuit and prepares the holding circuit at armature 13; and at armatures 12 and 15 disconnects line conductors 2 and 3 from the 55 windings of line relay 6 and ground and extends them by way of wipers 8 and 11, the bank contacts upon which they are standing, conductors 21 and 24, the resistance 29, and the armatures 35 and 38 to the windings of 60 line relay 25 of the trunk circuit TC. Line re-

lay 25 thereupon energizes over the calling line and closes at armature 30 a circuit for release relay 26. The electro-polarized relay 28, however, whose right hand winding is energized from the release trunk conductor 70 22 through resistance 42, and whose left hand winding is energized in multiple with the resistance 29, is not able to operate its armature at this time, owing to the fact that either winding alone is unable to operate the armature, and owing further to the fact that these windings are now energized in opposition to each other. Release relay 26 energizes responsive to the closure of its circuit at armature 31 of line relay 25 and places ground on 75 release trunk conductor 22 at armature 32, thereby completing a holding circuit through wiper 9 and armature 13 and its working contact for relay 5 before the slow acting line relay 6 has had time to deenergize. 80

In the trunk circuit TC, release relay 26 also closes at armature 33 a circuit for switching relay 46 of the secondary switch SS and stepping magnet 47 in series, and at armature 34 connects test wiper 54 to the 90 junction of the said switching relay 46 and stepping magnet 47. Accordingly, the secondary switch SS selects an idle trunk in the same manner as described above for the line switch C, which trunk is assumed to be the 95 one comprising conductors 56-59, inclusive, and extending to the director shown in Figs. 3-6, inclusive. When this idle trunk is reached, switching relay 46 energizes; opens the test circuit and places ground on test 100 wiper 54 at armature 50, thereby grounding conductor 58; prepares the impulse circuit at armature 51; and at armatures 48 and 49 closes a bridge across conductors 43 and 45 extending to the selector D. This bridge includes wipers 52 and 53, the bank contacts upon which they are standing, conductors 56 and 57, resistance 306, Fig. 4, and armatures 329 and 331 in multiple. Responsive to the closure of this bridge, line relay 63 of 105 the selector D energizes and closes a circuit for release relay 64 at armature 77, whereupon relay 64 energizes and prepares the switch for operation in the usual manner. 110

In the director, release relay 321 energizes 115 responsive to the ground potential being placed upon conductor 58 by the secondary switch SS through test wiper 54 and prepares the director for operation by operating its armatures 325-328, inclusive.

The upper winding of the electro-polarized relay 304 is now energized in multiple with relay 321 and the lower winding of the said relay is energized in multiple with resistance 306. Neither winding alone of this relay 120 has sufficient strength to operate the armatures. However, owing to the fact that the two windings are now energized in the same direction, the relay operates and prepares certain circuits to be subsequently closed. 125 130

The director is now in readiness to receive the first digit and when the first office digit 3 is dialled, line relay 25 deenergizes three times responsive to the three interruptions produced in its circuit by the calling device at substation A, and, upon each deenergization, line relay 25 opens the circuit of the slow acting release relay 26 at armature 30, but relay 26, being slow acting, maintains its armatures attracted throughout the series of interruptions. Upon each deenergization, line relay 25 also disconnects the combined switching and operating conductor from switching relay 27 at armature 31 and connects it to ground, thereby closing a circuit for vertical magnet 438 of the office register OR, Fig. 5, as follows: from ground by way of the resting contact and armature 31 of line relay 25, armature 51 and its working contact, wiper 55, the bank contacts upon which it is standing, conductor 59, series relay 202, Fig. 3, wiper 207 of the sequence switch S, the first associated bank contact, conductor 221, and vertical magnet 438 of the office register OR to battery. Responsive to the three impulses of current delivered to magnet 438 at this time, the shaft 431 of the office register OR is raised three steps through the medium of the vertical ratchet 432, and the wipers 451-454, inclusive, are carried opposite the third level of bank contacts. The shaft is retained in its operated position by the double dog 435. Relay 202 is energized in series with vertical magnet 438 upon the first impulse of current being delivered to the latter and, being slow acting, maintains its armature 214 attracted throughout the series of impulses. Relay 202 accordingly closes a circuit for the slow acting relay 203 which prepares at armature 215 a circuit for stepping magnet 204 of the sequence switch S.

At the end of the vertical movement of the office register OR, slow acting relay 202 deenergizes and completes at armature 214 a circuit through armature 215 for stepping magnet 204, whereupon the wipers 206 and 207 of the sequence switch S are advanced into engagement with the second set of bank contacts. A moment later, relay 203 deenergizes, opening the circuit of stepping magnet 204.

When the calling subscriber manipulates his calling device in accordance with the second office digit 3, the three impulses of current transmitted to the director over conductor 59 and through the series relay 202 are extended by wiper 207 of the sequence switch S by way of the second associated bank contact and conductor 222 to the long step rotary magnet 441 of the office register OR. Accordingly, the shaft 431 is rotated three long steps through the medium of the ratchet cylinder 434. The first rotary step of the shaft 431 carries the wipers 451-454, inclusive, into engagement with the first set of bank contacts in the third level; the second

step carries the wipers over the first three sets of contacts and into engagement with the fourth set of contacts; and the third step carries the wipers over the second three sets of bank contacts in the third level and brings them into engagement with the seventh set of bank contacts in the third level, which is the first set shown as wired up on the drawings, it being understood that all the contacts in the bank may be wired up to the IDF. The slow acting series relay 202 is again energized over the operating lead, and stepping magnet 204 of the sequence switch S is again energized at the end of the series of impulses, due to the conjoint action of relays 202 and 203, and the wipers 206 and 207 are advanced another step into engagement with the third set of bank contacts. Wiper 207 at this time extends the operating lead by way of conductor 231 to magnet 501 of the digit register DR-1, Fig. 6, and wiper 206 of the sequence switch S places ground on start conductor 235, the said wiper 206 being grounded through armature 325 of release relay 321 and through conductor 236. Responsive to the ground potential being placed upon conductor 235, the sender is started to transmit the first code digit. However, the description of the setting of the digit registers DR-1-DR-4, inclusive, in accordance with the subscriber digits of the number will be taken up before the operation of the sender is considered.

Responsive to the manipulation of the calling device in accordance with the first subscriber digit 1, one impulse of current is transmitted to stepping magnet 501 of the digit register DR-1, Fig. 6, and wiper 505 is advanced one step into engagement with the first impulse stop conductor 491. The sequence switch S is again advanced one step in the usual manner. Responsive to the dialling of the second subscriber digit 2, the digit register DR-2 is set accordingly; responsive to the dialling of the third subscriber digit 3, the third digit register DR-3 is set accordingly; and responsive to the dialling of the fourth subscriber digit 4, the fourth digit register DR-4 is set accordingly, the wipers 206 and 207 of the sequence switch S being advanced one step in the hereinbefore described manner at the end of each of the above mentioned digits. Accordingly, the wiper 207 is advanced into engagement with a dead contact and the wipers remain in this position until the director is freed.

Returning now to the point at which start conductor 235 was grounded at the end of the second office digit 3, the placing of the ground potential on start conductor 235 closes a circuit through the resting contact and armature 308, conductor 223, the wiper connecting relay 455, Fig. 5, conductor 224, and the short step rotary magnet 440 of the office register OR. Relay 455 accordingly

energizes and connects up the wipers 451-454, inclusive, to the relays *a-d*, inclusive, respectively. The contacts upon which the wipers of the office register are 5 now standing are connected to the intermediate distributing frame by means of the conductors 461-464, inclusive, and conductors 461 and 463 are grounded by means of the two jumpers extending therefrom to 10 the opposite side of the frame. Accordingly, relays *a* and *c* become energized and jointly place ground on the second impulse stop conductor 492 preparatory to terminating the first code digit 2.

15 As a further result of the ground potential being placed upon start conductor 235, a circuit is closed through the interrupter 305 and the resting contact and armature 354 of relay 324 for sending relay 322. Upon the first closure of the interrupter 305, relay 322 energizes and opens a point in the outgoing control circuit at armature 329. Armature 329, however, is shunted at this time by armature 331 and its resting contact, and the outgoing 20 control circuit is not opened. Relay 322 also closes at armature 330 a circuit for stepping magnet 338 of the sender. Stepping magnet 338 thereupon energizes and moves its pawl into engagement with the next notch in the 25 associated wiper driving ratchet wheel but does not move the wipers 340 and 341.

Upon the next opening of the interrupter 305, sending relay 322 deenergizes and opens the circuit of stepping magnet 338 at armature 330, whereupon the wipers 340 and 341 are advanced into engagement with the first 30 set of bank contacts. When this occurs, wiper 340 engages a grounded contact and pick-up relay 323 energizes; operates the two step 35 counting relay 303 the first step in a manner to be pointed out hereinafter; and at armature 331 removes the shunt from around armature 329 and its resting contact.

40 Since the shunt is now removed from around armature 329 and its resting contact of sending relay 322, stepping magnet 338 is energized in the usual manner at armature 330 upon each energization of sending relay 322 subsequent to the above mentioned energization of pick-up relay 323, and, in addition, the outgoing control circuit is opened at armature 329, permitting line relay 63 of the selector D to deenergize. Since magnet 338 is energized each time the outgoing 45 control circuit is opened, and since the wipers 340 and 341 are driven upon the back stroke of magnet 338, the said wipers 340 and 341 are advanced one step immediately following each opening in the outgoing control circuit, and, upon each step of the wipers, wiper 341 engages a different one of the impulse stop conductors 491-500, inclusive. No circuit, however, is closed for stop relay 324 when wiper 341 engages the bank contact in which stop conductor 491 termi- 50 nates, owing to the fact that stop conductor 491 is not grounded. Stop conductor 492, however, is grounded by the conjoint action of relays *a* and *c* as pointed out hereinbefore. Consequently, at the end of the second interruption in the outgoing control circuit at armature 329, wipers 340 and 341 advance another step and the latter engages the second impulse stop conductor 492, closing the following circuit for stop relay 324: from 55 ground by way of the right hand armature and working contact of relay *a*, Fig. 5, middle armature and resting contact of relay *b*, middle armature and working contact of relay *c*, the second impulse stop conductor 492, so the third contact in the bank of wiper 341, wiper 341, and stop relay 324 to battery. Stop relay 324 thereupon energizes; causes the complete energization of counting relay 303, in a manner to be hereinafter described, by opening its initial circuit at armature 336; and at armature 334 disconnects sending relay 322 from the interrupter 305 while the said relay is still in a deenergized condition, thereby terminating the first code digit 2. Stop relay 324 also closes a locking circuit for itself at armature 336 through the working contact and armature 332 of pick-up relay 323, and at armature 335 closes a restoring circuit for 60 stepping magnet 338 through interrupter contacts 339. Accordingly, the wipers 340 and 341 are rapidly spun around until wiper 340 passes off the last grounded bank contact, opening the restoring circuit of magnet 338. Wiper 340 also opens the circuit of pick-up 65 relay 323. This relay, however, is slow acting and maintains its armature attracted for an interval after its circuit is opened.

70 In the selector D, Fig. 1, line relay 63 is deenergized twice, momentarily, responsive to the two interruptions produced in the outgoing control circuit of the director as above described, and closes a circuit upon each deenergization for vertical magnet 71 as follows: from ground by way of armature 85 75 and its resting contact, armature 77 and its resting contact, armature 79 and its working contact, slow acting series relay 65, armature 36 and its resting contact, and vertical magnet 71 to battery. By the operation of vertical magnet 71, the wipers of the switch D are raised step by step until they stand opposite the second level of bank contacts. Relay 65 is energized in series with vertical magnet 71 and, being slow acting, it maintains its 80 armature attracted throughout the vertical movement.

75 By the conjoint action of series relay 65 and off normal contacts 76, which close upon the first vertical step of the switch, a circuit 85 is closed for stepping relay 66. Relay 66 thereupon energizes and closes a locking circuit for itself at armature 81. This locking circuit includes the interrupter contacts 75 and armature 85 and its resting contact in 90

addition to off normal contacts 76. Relay 66 also prepares a circuit for rotary magnet 72 at armature 82.

At the end of the series of impulses delivered to vertical magnet 71, slow acting series relay 65 deenergizes and completes the circuit of rotary magnet 72 at the normally closed contacts controlled by armature 80, whereupon rotary magnet 72 energizes and advances the wipers 68-70, inclusive, into engagement with the first set of bank contacts in the selected level, the second, and, near the end of its stroke, opens the circuit of stepping relay 66 at its interrupter contacts 72. Responsive to this, stepping relay 66 deenergizes and opens the circuit of rotary magnet 72 at armature 82, whereupon rotary magnet 72 deenergizes also and again closes its interrupter contacts 75. In case the trunk terminating in the first set of bank contacts is idle, switching relay 67 energizes immediately upon the above closure of the interrupter contacts 75 and seizes the trunk. In this case, however, it will be assumed that the trunk terminating in the first set of bank contacts is busy, in which case test wiper 69 engages a grounded test contact and switching relay 67 is short circuited. Also stepping relay 66 energizes through test wiper 69 and again closes a circuit for rotary magnet 72 at armature 82, whereupon rotary magnet 72 energizes again and advances the wipers 68-70, inclusive, into engagement with the next set of bank contacts.

This alternate operation of stepping relay 66 and rotary magnet 72 continues until an idle trunk is reached, which trunk, it will be assumed, is the one comprising conductors 87-89, inclusive, and extending to the selector E, whereupon switching relay 67, being no longer short circuited, energizes in series with stepping relay 66, stepping relay 66 not energizing on account of the high resistance of switching relay 67. Upon energizing, switching relay 67 disconnects ground from armature 77 of line relay 63 at armature 85, thereby opening the circuit of the slow acting release relay 64; shifts test wiper 69 from the test circuit to the holding circuit at armature 84; and at armatures 83 and 86 disconnects trunk conductors 43 and 45 from the windings of line relay 63 and extends them by way of wipers 68 and 70, the bank contacts with which they are in engagement, and conductors 89 and 87 to the windings of the line relay of the selector E. The line and release relays (not shown) of the selector E now energize in the usual manner and the latter prepares the switch for operation in the usual manner.

In the director, the electro-polarized relay 304 now retracts its armatures 316 and 317, owing to the fact that the current flow in its lower winding now opposes the current flow in its upper winding on account of the re-

versal made in conductors 87 and 89 leading from the banks of the selector D to the selector E, Fig. 1. Upon the retraction of armature 316 of relay 304, the two step counting relay 303, whose locking circuit is controlled by armature 316, deenergizes.

After the interval for which it is adjusted, slow acting pick-up relay 323 of the sender deenergizes and opens the locking circuit of stop relay 324 at armature 332. Stop relay 324, however, is slow acting also and does not deenergize immediately. Pick-up relay 323 also closes at armature 333 a circuit for the short step rotary magnet 440 of the office register OR, Fig. 5, as follows: from ground by way of armature 310 of relay 301, Fig. 4, and its resting contact, working contact and armature 337, armature 333 and its resting contact, conductor 224, and magnet 440 to battery. Responsive to the closure of this circuit, magnet 440 energizes and operates the ratchet wheel 433 through the medium of the member 436, advancing the wipers 451-454, inclusive, one short step. The closure of the above circuit results in the wiper connecting relay 455 being short circuited. When this occurs, relay 455 deenergizes and disconnects the wipers of the office register OR. This is done so as to permit the relays a-d, inclusive, to energize anew after each digit. Otherwise, one of these relays which is called upon to energize completely during one digit and to energize part way during the succeeding digit might remain operated completely from the half voltage battery which ordinarily operates it only half way.

In the sender, Fig. 4, the slow acting stop relay 324 deenergizes after an interval; opens the circuit of magnet 440 of the office register OR at armature 337; and at armature 334 again connects up the sending relay 322, whereupon the said sending relay 322 starts to vibrate again under the control of the interrupter 305 to send out the second code digit 4.

Responsive to the deenergization of the short step rotary magnet 440 of the office register OR, the circuit of the wiper connecting relay 455 is again closed at the interrupter contacts 439, whereupon the wipers are again connected up and relay a becomes energized over conductor 471 and through the associated IDF jumper. This relay applies ground to the fourth impulse stop conductor 494.

It may be pointed out conveniently at this time that the interval required for the slow acting relays 323 and 324 to fall back one after the other as above described is utilized to give time for the change-over and trunk-hunting operations to take place in the automatic switches, for example, the change-over and trunk-hunting operations of the selector D, Fig. 1, above described.

As above pointed out, the sender is again started and is now transmitting the second

code digit 4 in the desired number, and, at the end of the fourth interruption in the outgoing control circuit, wiper 341 of the sender is advanced into engagement with the bank 5 contact in which the fourth impulse stop conductor 494 terminates, thereby closing a circuit for stop relay 324 as follows: from ground by way of the right hand armature and working contact of relay *a*, Fig. 5, middle armature and resting contact of relay *b*, middle armature and resting contact of relay *c*, second armature and resting contact (counting from the left) of relay *d*, the fourth impulse stop conductor 494, the corresponding 10 contact in the sender bank, wiper 341, and stop relay 324 to battery. Responsive to the energization of stop relay 324, the second code digit is terminated in the usual manner.

Responsive to the transmission of the second code digit 4, the selector E, Fig. 1, raises its wipers opposite the fourth level and rotates them into engagement with an idle trunk, which trunk, it will be assumed, is the one comprising conductors 90-92, inclusive, 15 and extending to the repeater F. Responsive to the seizure of the repeater F, line relay 102 energizes over conductors 90 and 92 and closes a bridge across the associated outgoing trunk conductors extending to the distant selector G at armature 107. This bridge includes the right hand repeating coil windings and the upper winding of the electro-polarized relay 101. Relay 101, however, does not operate at this time on account of the fact 20 that the current flow in its upper winding is insufficient to operatively energize the relay. Responsive to the closure of the bridge across the outgoing trunk conductors at armature 107, the line and release relays (the latter not shown) of the distant selector G energize and 25 prepare the switch for operation. As a further result of the energization of line relay 102 of the repeater F, it closes at armature 106 a circuit for release relay 103, whereupon release relay 103 energizes and places ground on 30 release trunk conductor 91 at armature 108, and at armature 109 closes a circuit for the lower winding of the electro-polarized relay 101. Relay 101 now energizes and reverses 35 the trunk conductors 90 and 92. Relay 101 energizes at this time on account of the fact that the current flow in the upper winding assists the current flow in the lower winding 40 of the relay, due to the reversal in the leads connecting the line relay of the distant selector G with the associated trunk conductors.

In the director, the electro-polarized relay 304 again energizes responsive to the above reversal of the trunk conductors at the repeater F. Upon energizing, relay 304 prepares a locking circuit for the relays 302 and 60 303 at armature 316, and at armature 317 prepares an energizing circuit for the lower winding of relay 303.

After the usual interval, the slow acting

pick-up relay 323 again falls back, responsive to its circuit being opened by the return to normal of the wiper 340, and closes at armature 333 previously traced circuit for the short step rotary magnet 440 of the office 70 register OR, whereupon the wipers 451-454, inclusive, are advanced into engagement with the third and last set of bank contacts associated with the called office, and, as soon as relay 455 energizes again upon the subsequent deenergization of rotary magnet 440, 75 the wipers are again connected up and relays *a* and *d* energize over conductors 481 and 484, respectively, and the associated IDF jumpers. Relay *c* is energized also at this time over conductor 483 and through the associated IDF jumper. The relay *c*, however, gets only half as much current at this time as is required to operate it fully, owing to the fact that the jumper associated with conductor 483 extends to a half voltage battery bus-bar instead of to ground, and the drop across relay *c* is equal to the difference between the potential of the regular exchange battery and the potential of the half voltage bus-bar. 80 The battery associated with the half voltage bus-bar may be a separate battery of the same polarity as the regular exchange battery which is used to operate the relays *a-d*, inclusive, or it may be the grounded half of the regular exchange battery itself, depending upon which is found to be the most desirable in any particular case. At any rate, the current flow through the relay *c* at this time is 85 only half as great as it is when the free terminal of relay *c* is grounded. Accordingly, the relay *c* is operated only to the extent of the first step. Accordingly, its contacts marked 1 close while the remaining contacts marked 2 remain unoperated. As a result, the conductors 226 and 230 are joined together at the left hand armature of the relay *c* in order to 90 operate the transfer relay 301, as will be described hereinafter.

The sender is again started in the usual manner to transmit the third code digit 3, and, due to the fact that the electro-polarized relay 304 is now energized as above pointed out, the energization of pick-up relay 323 results in the two step relay 302 being operated through its first step in a manner to be explained hereinafter.

At the end of the third interruption in the outgoing control circuit, wiper 341 is advanced into engagement with the contact in which the third impulse stop conductor 493 is terminated, thereby closing a circuit for stop relay 324 as follows: from ground by way of the right hand armature and working contact of relay *a*, Fig. 5, the middle armature and resting contact of relay *b*, middle armature and resting contact of relay *c*, the second armature and working contact (counting from the left) of relay *d*, the 100 third impulse stop conductor 493, the asso- 105 110 115 120 125 130

ciated contact in the sender bank, wiper 341, and stop relay 324 to battery. Responsive to the closure of the above circuit, stop relay 324 energizes and terminates the digit being transmitted in the hereinbefore described manner, causing the wipers 340 and 341 to be returned to their normal positions. Also the initial circuit of the lower winding of relay 303 is opened at armature 336, resulting in the complete energization of relay 303 in a manner to be pointed out hereinafter. As a further result of the energization of stop relay 324, a circuit is closed at armature 337 for the transfer relay 301, owing to the fact that relay *c* is now energized through its first step only, as above pointed out. The circuit of transfer relay 301 is as follows: from ground by way of armature 310 and its resting contact, working contact and armature 20 337, armature 333 and its working contact, conductor 226, normally closed contacts controlled by the left hand armature of relay *c*, working contact and left hand armature of relay *c*, the associated resistance, conductor 25 230, and marginally adjusted relay 361, and the lower winding of relay 301 to battery. Relay 301 energizes over this circuit, but relay 361, being marginally adjusted, does not energize due to the high resistance associated 30 with the left hand armature of relay *c*. Relay 301, upon energizing, closes a locking circuit for its upper winding at armature 309; disconnects ground from the working contact of armature 337 of the stop relay at armature 35 310 and grounds the subscriber-digit stop-conductor control wiper 211 of the sequence switch *S'* through conductor 229; opens the circuit of the office register wiper connecting relay 455, Fig. 4, at armature 308; and prepares a stepping circuit for the magnet 208 of the sequence switch *S'* at armature 307. The circuits are now in readiness for the 40 transmission of the first subscriber digit in accordance with the setting of the first digit register DR-1 as soon as the slow acting stop relay 324 of the sender has fallen back.

Responsive to the transmission of the third code digit 3, line relay 102 of the repeater F, Fig. 2, is deenergized once responsive to each of the three interruptions produced in its circuit by the sender, and, upon each deenergization, opens the circuit of the line relay of the selector G. Accordingly, the selector G raises its wipers opposite the third level and selects an idle trunk, the trunk extending to the outgoing repeater F', for example. Accordingly, the relays of the repeater F' operate in the same manner as described for the relays of the repeater F and the distant thousands selector I in the called office is prepared for operation in the usual manner. However, owing to the fact that there is no reversal in the trunk leading from the repeater F' to the selector I, the relay in 60 the repeater F' which corresponds to the

electro-polarized relay 101 of the repeater F does not energize and accordingly there is now no reversal in the trunk conductors extending ahead from the repeater F, the reversed line relay of the selector G having 70 been cut off, and the electro-polarized relay 101 of the repeater F deenergizes and strengthens out the trunk conductors 90 and 92, due to the fact that the current flow in its upper winding now opposes the current flow 75 in its lower winding.

In the director, the electro-polarized relay 304 now deenergizes responsive to the reversal of the current flow back to normal by the electro-polarized relay of the repeater 80 F and opens the locking circuit of the two step relay 303 at armature 216, whereupon relay 303 deenergizes also.

After the usual interval, the sender is again started upon the deenergization of the 85 slow acting stop relay 324. At this time, since the transfer relay 301 is energized, the energization of pick-up relay 323 results in the closure of a circuit for the stepping magnet 208 of the sequence switch *S'* as 90 follows: from ground by way of the working contact and armature 322 of pick-up relay 323, armature 336 and its resting contact, armature 307 and its working contact, conductor 238, and stepping magnet 208 to battery. Stepping magnet 208 thereupon energizes and moves the associated pawl into engagement with the next notch in the wiper driving ratchet wheel but does not move the 95 wipers 210 and 211.

At the end of the single impulse representing the first subscriber digit 1, wiper 341 of the sender is advanced into engagement with the bank contact in which the first impulse stop conductor 491 is terminated, whereupon stop relay 324 is energized over the following circuit: from ground by way of armature 310 and its working contact of transfer relay 301, stop conductor control wiper 211, the first subscriber digit stop conductor 241, wiper 505 of the digit register DR-1, the second associated bank contact, the first impulse stop conductor 491, the corresponding contact in the sender bank, wiper 341, and stop relay 324 to battery. Upon 105 energizing, stop relay 324 disconnects the sending relay 322 and closes the usual restoring circuit for stepping magnet 338 at armatures 334 and 335, respectively, and, in addition, opens the circuit of stepping magnet 208 110 of the sequence switch *S'* and closes its local self-locking circuit at armature 336. Responsive to the opening of the circuit of stepping magnet 208, the wipers 210 and 211 115 of the sequence switch *S'* are advanced one 120 step and the stop conductor control wiper 211 removes ground from the first subscriber digit stop conductor 241 and places ground instead on the second subscriber digit stop conductor 242.

Responsive to the transmission of the first subscriber digit 1, the thousands selector I in the called office raises its wipers opposite the first level of bank contacts and selects an 5 idle trunk extending to a hundreds selector, the trunk extending to the hundreds selector J, for example. Accordingly, the selector J is prepared for operation in the usual manner.

In the director, the sender is again started 10 in the usual manner and transmits the second subscriber digit 2, which is terminated at the end of the second interruption in the outgoing control circuit responsive to the energization of stop relay 324 over the following 15 circuit: from ground by way of armature 310 of the transfer relay 301 and its working contact, stop conductor control wiper 211 of the sequence switch S', conductor 242, wiper 506 of the second digit register DR-2, the 20 third associated bank contact, the second impulse stop conductor 492, the corresponding contact in the sender bank, wiper 341, and stop relay 324 to battery. The wipers of the 25 sequence switch S' are advanced one step responsive to the opening of the circuit of stepping magnet 208 at armature 336 of stop relay 324.

Responsive to the transmission of the second subscriber digit 2, the hundreds selector J, Fig. 2, raises its wipers opposite the second level and selects an idle trunk in the usual manner, which trunk, it will be assumed, is the one comprising conductors 121-123, inclusive, and extending to the connector K. Accordingly, line relay 125 becomes energized and closes at armature 134 a circuit for release relay 126. Upon energizing, release relay 126 prepares the switch for operation by attracting armatures 135-137, 40 inclusive.

Since conductors 121 and 123 are reversed between the connector K and the banks of the selector J, the electro-polarized relay (not shown) in the repeater F', which relay corresponds to the electro-polarized relay 101 of the selector F, energizes and reverses the incoming trunk conductors, whereupon the direction of current flow in the upper winding of the electro-polarized relay 101 of the repeater F is reversed and the said relay 101 operates, reversing trunk conductors 90 and 92. Responsive to the reversal of the trunk conductors 90 and 92, the electro-polarized relay 304, Fig. 4, responds, operating armatures 316 and 317.

The sender is again started in the usual manner to send out the third subscriber digit 3 in the desired number and pick-up relay 323 energizes as usual. At this time, since relay 60 304 is operated, a circuit is closed through the working contact and armature 317 and armature 315 and its resting contact for the lower winding of the two step relay 303 in multiple with magnet 208 of the sequence switch S'. Accordingly, relay 303 energizes half way

and operates its lightly adjusted first step armature 314, the stiffly adjusted second step armature 315 not operating at this time on account of the small number of turns of relatively high resistance wire contained in the 70 lower winding of relay 303. Upon operating, armature 314 closes a locking circuit for relay 303, including the upper winding thereof, armature 316 and its working contact, and the grounded release trunk conductor 58. 75 This locking circuit does not become effective at this time, however, owing to the fact that the initial circuit of the relay is still established, short circuiting the upper winding of the relay.

At the end of the third interruption produced in the outgoing control circuit by the sending relay 322, the wipers 340 and 341 of the sender are advanced into engagement with the fourth set of associated bank contacts, whereupon stop relay 324 energizes over the following circuit: from ground by way of the stop conductor control wiper 211 of the sequence switch S', the third subscriber digit stop conductor 243, wiper 507 of the 90 digit register DR-3, the fourth associated bank contact, the third impulse stop conductor 493, the corresponding contact in the sender bank, wiper 341, and stop relay 324 to battery. Stop relay 324, upon energizing, 95 terminates the third subscriber digit in the usual manner, and, in addition, opens the circuit of stepping magnet 208 of the sequence switch S' and of the lower winding of the two step relay 203 and closes its usual locking circuit at armature 336. When the initial circuit of relay 303 is opened, its local locking circuit, including its two windings in series, becomes effective, whereupon the magnetic pull of the core is increased to 100 such an extent that the second step armature 315 is operated, disconnecting the initial energizing conductor from the junction of its own winding and extends it through the resting contact and armature 315 to the junction of the windings of the two step counting relay 302.

In the connector K, line relay 125 is deenergized three times responsive to the transmission of the third subscriber digit 3 and, upon each deenergization, closes a circuit for vertical magnet 158, the circuit at the time of its first closure being as follows: from ground by way of armature 134 and its resting contact, armature 137 and its working contact, contact of off normal spring 157 and said spring, slow acting series relay 127, and vertical magnet 158 to battery. By the operation of vertical magnet 158, the wipers 152-154, inclusive, are raised opposite the third level of bank contacts, which is the level in which the line of substation A' terminates. Relay 127 is energized in series with vertical magnet 158 and, being slow acting, maintains its armature 138 attracted 120 125 130

throughout the vertical movement, and maintains its own circuit and that of vertical magnet 158 intact after the off normal springs have shifted, as they do upon the first vertical step. At the end of the vertical movement, slow acting series relay 127 deenergizes and transfers the operating circuit from vertical magnet 158 to rotary magnet 159.

10 In the director, the sender is again started to transmit the fourth and last subscriber digit 4, and, upon the energization of pick-up relay 323, the usual circuit for stepping magnet 208 of the sequence switch S' is closed at 15 armature 332. Also the lower winding of the two step counting relay 302 is energized through the working contact and armature 317 of relay 304, armature 315 and its working contact, and the resting contact and armature 313. Relay 302, being similar to relay 303, operates only part way and brings its first step armature 311 into engagement with the associated contact, thereby preparing the usual locking circuit including both 25 windings in series.

At the end of the fourth interruption produced in the outgoing control circuit by sending relay 322, stop relay 324 is energized over the following circuit: from ground by 30 way of wiper 211 of the sequence switch S', the fourth subscriber digit stop conductor 244, wiper 508 of the fourth digit register DR-4, the fifth associated bank contact, the 35 fourth impulse stop conductor 494, the corresponding contact in the sender bank, wiper 341, and stop relay 324 to battery. Responsive to the energization of relay 324, the digit being transmitted is terminated in the usual manner and the circuit of magnet 208 of the 40 sequence switch S', as well as the circuit of the lower winding of the two step counting relay 302 is opened at armature 336. Incidentally, the wipers of the sequence switch S' are advanced responsive to the deenergization of 45 the magnet 208, and, responsive to the opening of the initial circuit of relay 302, the locking circuit including both windings of the said relay and armature 311 and its working contact becomes effective, whereupon the relay 50 operates the remaining distance; opens a further point in its initial circuit at armature 313; and at armature 312 places ground on the combined operating and switching conductor 59, closing a circuit over the said conductor 59, the corresponding contact in the bank of wiper 55 of the secondary switch SS, Fig. 1, wiper 55, working contact and armature 51, armature 31 and its working contact, and switching relay 27 to battery. Relay 27 55 thereupon energizes and closes a locking circuit for itself at armature 37; separates series relay 65 of the selector D from vertical magnet 71 at armature 36 for a purpose to be pointed out hereinafter; disconnects conductors 21 and 24 from the windings of line

relay 25 at armatures 35 and 38, at the same time joining these conductors with the conductors 43 and 45 of the selector D and disconnecting the latter from the control bridge including the contacts of the sending relay 70 322 of the sender. The switches involved in the connection are now held up from the called line rather than from the above mentioned control bridge.

Responsive to line relay 25 of the trunk 75 circuit TC being disconnected by switching relay 27 as above pointed out, the said relay deenergizes and opens the circuit of release relay 26 at armature 30. After the interval for which it is adjusted, release relay 26 de- 80 energizes and removes ground from release trunk conductor 22 at armature 32, leaving the said conductor grounded through the release trunk conductor connection extending to the repeater F. Release relay 26 also 85 opens a further point in the test circuit of the secondary switch SS at armature 34, and at armature 33 opens the circuit of switching relay 46, whereupon relay 46 deenergizes, 90 freeing the director.

In the director, relays 301-304, inclusive, and relay 321 deenergize responsive to the removal of the ground potential from the release trunk conductor 58 when the director is freed by the secondary switch SS, and relay 321 closes at armature 325 a restoring circuit for the sequence switch S' which includes conductor 237, the contacts in the bank of wiper 210, wiper 210, interrupter contacts 209, and stepping magnet 208. Stepping magnet 208 accordingly interrupts its own circuit and advances the wipers 210 and 211 step by step until the former passes off the last grounded bank contact. Release relay 321 also closes the normal restoring circuit 100 of the sender at armature 326, which is effective in restoring the wipers 340 and 341 to normal in case the director is freed while a digit is being transmitted, in which case the restoring circuit at armature 335 of stop relay 324 is not available. As a further result of the deenergization of release relay 321, ground is placed on the release conductor 225 at armature 327, closing a circuit through off normal contacts 216 for release magnet 205 105 of the sequence switch S. Magnet 205 thereupon energizes and restores the wipers 206 and 207 to normal, whereupon its circuit is opened at off normal contacts 216. As a further result of the ground potential being placed on release conductor 225, circuits are closed through off normal contacts 513-516, inclusive, for the release magnets 509-512, inclusive, of the digit registers DR-1-DR-4, 110 inclusive, respectively, whereupon the wipers 505-508, inclusive, are restored to their respective normal positions and the said off normal contacts 513-516, inclusive, open the circuits of the respective associated release magnets. As a still further result of the ap- 115 120 125 130

plication of the ground potential to release conductor 225, a circuit is closed through release magnet 442 of the office register OR and off normal contacts 443, whereupon release 5 magnet 442 energizes and withdraws the double dog 435, permitting the shaft 431 of the office register to be rotated and then dropped to normal in the usual manner for switches of the same general type. The di- 10 rector is now completely restored to normal position and is ready to be used in handling another call.

In the connector K, Fig. 2, line relay 125 is deenergized four times responsive to the 15 transmission of the last digit 4 in the number and, upon each deenergization, transmits an impulse of current to rotary magnet 159 over the following circuit: from ground by way 20 of armature 134 and its resting contact, armature 137 and its working contact, normally open contacts controlled by off normal spring 157, armature 138 and its resting contact, resting contact and armature 143, armature 150 and its resting contact, and rotary magnet 25 159 to battery. By the operation of rotary magnet 159, the wipers 152-154, inclusive, of the connector K are rotated step by step until they come into engagement with the fourth 30 set of bank contacts in the third level, which is the set in which the line of substation A' terminates. Relay 130 is energized in multiple with rotary magnet 159 and, being slow 35 acting, maintains its armature attracted throughout the rotary movement. Upon energizing, relay 130 disconnects test wiper 153 from the upper winding of switching 40 relay 131 and connects it to busy relay 129 instead, and at armature 146 places a shunt around armature 143 and its resting contact so as to guard the circuit of rotary magnet 45 159 against the possibility of being opened in case busy relay 129 energizes due to test wiper 153 passing over the grounded bank contacts associated with busy lines.

From this point the operation of the connector K depends upon whether the called line is busy or idle. Assuming first that it is busy, busy relay 129 is energized when the 50 wipers of the connector come to rest upon the bank contacts in which the called line terminates, and, when slow acting relay 130 de-energizes, a locking circuit is closed at the normally closed contacts controlled by armature 145 for busy relay 129 as follows: from ground by way of the working contact and armature 136, armature 142 and its working contact, normally closed contacts controlled by armature 145, and busy relay 129 to battery. Busy relay 129 maintains open 55 the circuit of relay 130 and rotary magnet 159 at armature 143 so as to prevent any further operation of the rotary magnet in case the calling subscriber again manipulates his calling device. Busy relay 129 also connects the 60 busy lead 161 at armature 144 to the lower

heavy talking conductor, thereby transmitting an audible busy signal back to the calling subscriber to inform him that he cannot obtain the desired connection for the time being. Upon hearing this busy signal, the 70 calling subscriber is expected to replace his receiver, whereupon the connection is released in a manner to be described hereinafter.

Assuming now that the called line is idle, 75 busy relay 129 is not energized when the called line is reached, and, upon the deenergization of slow acting relay 130, a circuit is closed for the upper winding of switching relay 131 as follows: from ground by way 80 of the working contact and armature 136, armature 142 of busy relay 129 and its resting contact, upper winding of switching relay 131, resting contact and armature 145, test wiper 153, the bank contact with which 85 it is in engagement, switching relay 171 of line switch C', and the associated stepping magnet to battery. Relays 131 and 171 energize in series over this circuit and relay 171 disconnects the normal ground and battery 90 connections from the called line, but, due to a mechanical inter-locking device (not shown) between the armature of relay 171 and the armature of relay 172, relay 171 is operated only about half way and the line 95 switch wipers are not connected up.

In the connector K, relay 131, upon energizing, closes a locking circuit for its lower winding at armature 149; places direct ground on test wiper 153 at armature 148; disconnects relay 130 and magnet 159 at armature 150; and at armatures 147 and 151 connects up the line wipers, whereupon ringing current from the grounded generator lead 160 is projected out over line wiper 154 and 100 returns by way of line wiper 152, and the upper winding of ring-cut-off relay 238. Relay 238 is not operated at this time, however, due to its special slow acting construction 105 and due to the fact that no direct current flows in this circuit owing to the condenser which is in series with the bridged bell at the called substation A'. The small condenser 181 permits enough of the return ringing current to leak back to the talking circuit 110 to give the calling subscriber an audible indication that the called subscriber's bell is being rung.

Considering now the electro-polarized relay 28, associated with the trunk circuit TC, 115 this relay is not operated after the connection is switched through by switching relay 27. Ordinarily, it would be expected that this relay would operate due to the fact that conductors 120 87 and 89 leading to the selector E are reversed. This reversal, however, is compensated for by the reversal at the electro-polarized relay 101 of the repeater F, which relay 125 is operated due to the reversal above mentioned in the repeater F', which reversal in 130

turn is brought about by the reversal in the trunk conductors 121 and 123 leading from the banks of the selector J to the connector K.

When the called subscriber responds to the ringing of his bell by removing his receiver, a direct current bridge is closed across the conductors of his line through the transmitter and receiver, whereupon the ring-cut-off relay 238 energizes over the called line and through 10 the grounded generator lead 160 and closes a locking circuit for its lower winding at armature 140, and at armatures 139 and 141 disconnects the wipers 152 and 154 from its own winding and the lead 160 and connects them 15 instead to the windings of the back bridge relay 124. When this occurs, relay 124 energizes and again reverses conductors 121 and 123 as regards their connection with the windings of the line relay 125. When this occurs, 20 the current flows through the conductors 121 and 123 in the normal direction and the electro-polarized relay (not shown) of the repeater F' retracts its armatures, reversing the associated trunk conductors back to normal. 25 Responsive to this, the electro-polarized relay 101 of the repeater F retracts its armatures, reversing the current flow in the conductors 90 and 92 back to normal. Responsive to this latter operation, the electro-polarized relay 30 28 attracts its armatures due to the reversal in conductors 87 and 89 of the selector E; short circuits the resistance 42 at armature 41 so as to enable the right hand winding of the relay to maintain the relay operated independent of the left hand winding; places a 35 shunt around its left hand winding and the resistance 27 at armature 40; and at armature 39 closes a circuit for the magnet 18 of the meter M over conductor 23, the corresponding 40 contact in the bank of wiper 10, wiper 10, and the working contact and armature 14. The magnet of the meter M now operates to register the completed connection. The calling and called subscriber may now converse 45 with each other as desired.

When the conversation is completed, the two subscribers hang up their receivers and, when the receiver is replaced at the called substation A', back bridge relay 124 deenergizes 50 and reverses the trunk conductors 121 and 123 back to their original standing, whereupon the electro-polarized relay (not shown) of the repeater F' again operates and reverses the conductors extending back to the repeater F, 55 whereupon the electro-polarized relay 101 operates and reverses the conductors 91 and 92. This, however, does not have any effect upon the electro-polarized relay 28 associated with the trunk circuit TC, owing to the fact that 60 the left hand winding of the said relay 28 is now short circuited.

When the receiver is replaced at substation A, line relay 102 of the repeater F deenergizes; opens the circuit of release relay 103 at armature 106; and at armature 107 opens the

circuit of the line relay (not shown) of the repeater F'. When this occurs, the line relay of the repeater F' opens the circuit of the associated release relay and the circuit of line relay 125 of the connector K. Line relay 125 70 thereupon deenergizes and opens the circuit of release relay 126.

In the repeater F, responsive to the opening of its circuit, release relay 103 deenergizes after the interval for which it is adjusted and 75 opens the circuit of the lower winding of the electro-polarized relay 101 at armature 109, whereupon relay 101 deenergizes; and at armature 108 removes ground from release trunk conductor 91, whereupon switching relay 67 of the selector D, switching relay 27, the electro-polarized relay 28 of the trunk circuit TC, and switching relay 5 of the line switch C deenergize. Responsive to the de- 80 energization of switching relay 67 of the selector D, release magnet 73 energizes through armature 85 and its resting contact, armature 77 and its resting contact, armature 79 and its resting contact, and off normal contacts 74. The wipers of the selector D are restored to 85 normal in the usual manner responsive to the operation of release magnet 73, whose circuit is again opened at off normal contacts 74 when the wipers of the switch reach their normal position. 95

Responsive to the deenergization of the electro-polarized relay 28, and to the deenergization of switching relay 5 of the line switch C, the circuit of the magnet 18 of the meter M is opened at armatures 39 and 14. 100

After the interval for which it is adjusted, the release relay (not shown) of the repeater F', Fig. 2, deenergizes and permits the selector G to be restored to normal position in the usual manner. 105

After the interval for which it is adjusted, release relay 120 of the connector K deenergizes and removes ground from release trunk conductor 122 at armature 135, permitting the selectors I and J to be restored to normal 110 position in the usual manner. As a further result of the ground potential being removed from release trunk conductor 122, relays 128 and 131 deenergize and the latter disconnects the switch wipers; the removal of the ground from wiper 153 permitting relay 171 of the line switch C' to deenergize. Release relay 126 also completes at armature 137 a circuit including armature 134 and off normal contacts 156 for release magnet 155, whereupon 120 the wipers of the connector K are restored to normal position in the usual manner. The entire connection is now released and the apparatus used therein is ready to be used in another call. 125

In order to enable certain desirable features of the present invention to be understood best, it will be assumed that a subscriber, the subscriber at substation A, starts to make a call, but, after removing his re- 130

ceiver, fails to manipulate his calling device and leaves the receiver off the hook. In order to explain this best, it will be assumed that, upon the removal of the receiver at substation 5 A, the line switch C selects the trunk extending to the selector D, and that the secondary switch SS selects the director shown in Figs. 3-6, inclusive. Accordingly, the various relays of the switches are operated in the hereinbefore described manner and the circuits are now in readiness for the first digit in the desired number to be transmitted, but, as assumed above, the subscriber does not manipulate his calling device, and, unless special arrangements were made to prevent this, the director would remain tied up indefinitely. Accordingly, the two step relay 201 and the associated circuit arrangements have been provided to cut off the director and extend the 20 calling line to the first selector D after a reasonable amount of time has been given for the calling subscriber to dial the first digit. The detailed description of the operation will now be given.

25 When the release relay 321 of the director, Fig. 4, energizes responsive to the release trunk conductor 58 becoming grounded when the director is seized, the common conductor 351 is connected to conductor 228 at armature 328, and, as soon after this occurs as the projection on the periphery of the slowly rotating cam 352 comes into engagement with the associated contact spring, conductor 351 becomes grounded, thereby closing a circuit 35 through the working contact and armature 328, conductor 228, armature 213 and its resting contact for the lower winding of the two step relay 201. Relay 201 is similar to the relays 302 and 303 and accordingly operates 40 through the first step only and prepares the usual locking circuit for itself at armature 212. Shortly after this occurs, the projection on the periphery of the cam 352 passes from under the associated contact spring, opening 45 the initial circuit of relay 201. Responsive to this, relay 201 pulls up completely, its two windings being energized in series over the following circuit: from ground by way of armature 325 of relay 321 and its working contact, conductor 236, wiper 206 of the sequence switch S, armature 212 and its working contact, and relay 201 to battery. Relay 201, upon operating completely, opens a further point in its initial circuit and connects conductor 228 with the combined switching 50 and operating conductor 59. The circuits are now in readiness for switching relay 27 of the trunk circuit TC to operate to switch the connection through to the selector D and 55 cut off the director in case the first digit is not dialled before the common conductor 351, Fig. 4, is again grounded.

In case the first digit is dialled prior to this time, the wipers 206 and 207 are advanced at 60 the end of this digit in the hereinbefore de-

scribed manner, and the locking circuit of relay 201 is opened when wiper 206 passes off the first grounded bank contact, whereupon relay 201 deenergizes. With its locking circuit opened and its upper winding disconnected, relay 201 cannot be operated through its second step again and the director is cut off in the hereinbefore described manner when a complete number is called. Assuming, however, that the first digit is not dialled 70 before conductor 351 is again grounded, the ground potential is extended through the working contact and armature 328, conductor 228, and armature 213 and its working contact to the combined switching and operating conductor 59. Responsive to this conductor being grounded, switching relay 27 of the trunk circuit TC is operated and the director is freed in the hereinbefore described manner.

75 As pointed out hereinbefore, series relay 65 is disconnected from vertical magnet 71 at armature 36 of switching relay 27. Accordingly, the calling subscriber is prevented from operating the selector D directly and the connection cannot be extended any further, and 80 the fact that a "permanent" exists on the selector D may be detected by the exchange attendant in any well known or desired manner.

85 It may well be pointed out at this time just why the two reversals in the trunk conductors employed when a connection is set up between the subscriber at substation A and the subscriber at substation A' are made and why they are made where they are. Starting first 95 with the reversal in the trunk conductors 121 and 123 extending between the bank of the selector J, Fig. 2, and the connector K, this reversal, as is apparent from the foregoing, is made in order to operate the electro-polarized relay 304 of the director, Fig. 4, so as to connect up the counting relays 302 and 303 100 to enable them to cut off the director at the end of the second digit dialled after such reversal is encountered. This permits of a variable number of selectors being used before the connector is encountered. For example, 105 a telephone number may be called which contains two office digits and only two or three subscriber digits, depending upon the size of 110 the called office. In either case, however, the trunk conductors leading to the connector when such office is called are reversed and the director is automatically cut off in the hereinbefore described manner.

115 The second reversal, that is, the one between the bank of selector D and selector E, is necessary in order to compensate for the first reversal after the director is cut off and before the called man answers so that the 120 calling subscriber's meter will not be prematurely operated. In a flat rate system, without meters, this second reversal perhaps could be omitted, although it would still be necessary if reverse current supervision were 125 130

used on the outgoing trunks from operators' positions. As to the reason for inserting the second reversal at the point indicated, it is placed after the selector D rather than before 5 in order not to interfere with the arrangement for switching "permanents" through to the first selectors. With the reversals just ahead of the second selectors all trunks are straight as far as the first selectors and any 10 line can be switched through without operating the associated meter. It should be noted also that the arrangement for opening the circuit of the vertical magnet of the selector D by the switching relay 27, which of 15 course, is applied to all first selectors, prevents any subscriber from extending his line to a reversed trunk by directly operating a first selector, which, if it could happen, would 20 at once operate his meter.

Attention is called to the fact that in the ordinary operation of the director a single reversal has no effect unless it is followed by the transmission of two digits while the trunk remains reversed, because of the circuit arrangement by which the polarized relay 304 controls the locking circuit of relay 303. Thus the effect of the reversal, in the control circuit, which operates the polarized relay 304 when the director is seized, is wiped out 25 by the reversal just ahead of the selector E, and, in a similar manner, the reversal at the line relay of selector G is rendered ineffective by the immediately succeeding reversal which takes place on the energization of the switching relay of this selector. The utility of the 30 reversal in the connections of the line relay of the selector G will be pointed out subsequently.

It is common practice in certain large telephone systems to provide an operator who takes care of complaints from the subscribers. This operator is known as the "complaint" operator. It is also common practice to provide an operator who gives information to 35 those subscribers who desire it. These two operators, together with any other special operators which may be provided for various reasons, are generally located in the same office and may be reached from different levels of the same group of selectors. It is assumed that each of the trunks from the first 40 level of the selector G, Fig. 2, leads to a special selector, which selector in turn has access to trunks leading to the positions of the complaint, information, and any other 45 special operators that may be provided. It is assumed further that the numbers of each of these various operators contain three digits, two digits which correspond to office 50 digits and one digit which corresponds to a subscriber digit. Accordingly, when one of these numbers is called, the director in use transmits the required number of code digits 55 responsive to the first two digits dialled, and retransmits the third digit dialled to 60

operate the special selector reached by way of the selector G, Fig. 2, after which the director is cut off automatically in a manner to be pointed out hereinafter.

As representative of all calls to the special 70 operators, a call to the information operator will be chosen and for this purpose it will be assumed that the subscriber at substation A desires to learn the number of a certain other subscriber who is not as yet listed in the telephone directory. It will be assumed further that, when the subscriber at substation A removes his receiver, the line switch C selects the trunk circuit TC, and that the secondary switch SS selects the director shown in Figs. 80 75 85 90 95 3-6, inclusive. That being the case, the above mentioned director is prepared for operation in the usual manner and, when the first two digits of the number are dialled, the office register OR is raised opposite the desired 90 level and rotated into engagement with the desired set of bank contacts. This set of contacts is not shown wired up but may be wired up similar to the ones that are shown 95 wired up, except of course that the cross connections at the IDF must be such as to produce the necessary code digits. The calling subscriber now manipulates his calling device in accordance with the third and last digit in the desired number, resulting in the 99 digit register DR-1, Fig. 6, registering such digit.

The sender is started in the usual manner at the end of the registration of the second digit and transmits the code number necessary to operate the selector D, the selector E, and the selector G through the repeater F. The electro-polarized relay 304, Fig. 4, is energized in the usual manner when the selector G is seized, owing to the fact that the 105 electro-polarized relay 101 of the repeater F reverses conductors 90 and 92 responsive to the reversal in the line relay connections of the selector G. Accordingly, a circuit is prepared for the two step counting relay 303 110 and the said relay is operated through its first step at the beginning of the digit which operates the selector G, and is operated through its second step in the usual manner 115 at the termination of the digit transmitted to the selector G.

In the previously described example, when the call was for the subscriber at substation A', the selector G was operated to the third level to seize the repeater F', in which case the electro-polarized relay 101 was forced to restore owing to the fact that the trunk extending to the repeater F' is straight and not reversed. This permitted the electro-polarized relay 304 of the director, Fig. 4, to restore and unlock the two step relay 303. In the present case, however, the selector G is operated to its first level and seizes a special selector whose trunk conductors are reversed as shown. Accordingly, the electro-polar- 120 125 130

ized relay 101 of the repeater F does not restore and relays 303 and 304 of the director are maintained energized.

The sender now transmits the digit stored 5 on the first digit register DR-1, Fig. 6, thereby operating the special selector seized by the selector G to extend the connection to the information operator in the usual manner. The two step relay 302 is operated 10 through its first step as hereinbefore described at the beginning of the transmission of the above digit and is operated through its second step at the termination of such digit, thereby placing ground on conductor 15 59, causing the director to be cut off in the hereinbefore described manner.

Although it is desired to make the control of the cut off of the director revertive from the switches involved in the connection, it is sometimes permissible to have the 20 cut off of the director controlled from the director itself when the number called contains office digits only. It has been assumed that the number assigned to the toll recording 25 operator is such a number. The trunks to the toll recording operator are taken from the second level of the selector G, Fig. 2, and it will now be assumed that the subscriber at substation A desires to communicate with the toll recording operator. Assuming that, when the subscriber at substation A removes his receiver, the line switch C seizes the trunk circuit TC and the secondary switch SS seizes the director shown 30 in Figs. 3-6, inclusive, the said director is prepared for operation in the usual manner.

The subscriber at substation A now manipulates his calling device in accordance with the two digits in the desired number, whereupon the office register OR is operated to the 40 correct level and then to the correct set of contacts to register such digits. The sender is now started to transmit the code digits necessary to trunk the call through the selectors D, E, and G to the toll recording operator's position. These digits are determined in the usual manner by the way in which the bank contacts selected are cross-connected on the IDF.

At the end of the third code digit 2, transfer relay 301 is operated over its previously 50 traced circuit which includes conductors 230 and 226 and one of the resistances associated with the relays *a-d*, inclusive. In the present case, however, it is desired to operate the marginally adjusted relay 361 also. Accordingly, instead of connecting only one 55 of the spare conductors, corresponding to conductor 483, to the half voltage bus-bar, two such conductors are connected to the said bus-bar, resulting in two of the relays *a-d*, inclusive, being operated half way only in which case the circuit of relay 361 and relay 60 301 in series includes two of the resistances associated with the relays *a-d*, inclusive, in

multiple. This permits sufficient current to flow to energize the marginally adjusted relay 361, which relay closes a locking circuit for itself at armature 363 and at armature 362 places ground on conductor 59, resulting 70 in the director being cut off in the hereinbefore described manner.

It occasionally happens that a number contains one or more subscriber digits and that no connector switch is encountered, trunks to 75 the desired destination being taken from selector banks. Such a case has already been described in connection with a call to the information operator. However, the trunks leading to that operator's position come from 80 the banks of a special selector reached from the first level of the selector G and it is always desired to switch following the operation of this special selector, and no special arrangements need be provided beyond reversing the line relay connections in the selector G and the trunk extending to the special selector. However, in the case of calls to the 85 fire department, the trunks are taken from the second level of the selector G', reached 90 from the third level of the selector E, which selector G' is not a special selector, and it is, accordingly, not always desired to switch following a digit transmitted to the selector G', it being assumed that trunks from levels 95 other than the second lead to other selector switches. It is further assumed that it is not expedient or desirable to reverse the connections of the line relay of the selector G' as is done in the case of the selector G. This 100 may well be due to the fact that the trunks from one of the levels of the selector G' other than the second are reversed, in which case a reversal of the line relay of the selector G' would result in a premature switching operation when a call is made to one of the said other levels. With the above facts in mind, it will be seen that when a call is made to the fire department some special arrangements 105 not heretofore pointed out must be made in 110 order to free the director. This is done by assigning two extra digits to the number of the fire department. These digits are dialled as subscriber digits and, since they are not needed for trunking purposes, they are absorbed by the digit absorber digit DA. Accordingly, since the trunk leading to the digit absorber DA is reversed, the director is cut off at the end of the second absorbed digit.

It will probably enable this operation to be 115 understood a little better if a general description of a call to the fire department is made. For this purpose it will be assumed that the subscriber at substation A desires to call the fire department. Assuming further 120 that the line switch C seizes the trunk extending to the selector D and that the secondary switch SS seizes the director shown in Figs. 3-6, inclusive, the director is prepared for 125 operation in the usual manner. The calling 130

subscriber now dials the two office digits in the number of the fire department, resulting in the office register OR being operated to register such digits, and then dials the three subscriber digits of the number, resulting in the digit registers DR—1—DR—3, inclusive, being operated to register such digits. The sender is started at the end of the second office digit and under the control of the office register OR transmits the two code digits necessary to operate the selector D to seize the selector E and the selector E in turn to seize the selector G'.

The sender now transmits the first subscriber digit, which is stored on the digit register DR—1, resulting in the selector G' raising its wipers to the second level to seize a trunk line extending to the fire department, the trunk line terminating in the digit absorber DA, for example. This digit absorber, it may be pointed out, may be of the type shown and described in the United States patent to Baer, No. 1,463,934, granted August 7, 1923. Since the trunk extending from the bank of the selector G' to the digit absorber DA is reversed, the electro-polarized relay 304 of the sender, Fig. 4, energizes and prepares the circuit of the first two step counting relay 303. Accordingly, at the end of the transmission of the next registered digit, which digit is absorbed by the digit absorber DA as disclosed in the Baer patent, relay 303 energizes through its second step and prepares the circuit for the second two step counting relay 302. That being the case, at the end of the next digit, which digit also is absorbed by the digit absorber DA, the two step relay 302 energizes completely and closes the switching circuit at armature 312, resulting in the connection being switched through and in the director being freed in the hereinbefore described manner.

In the digit absorber DA, the connection has now been closed through to the trunk leading to the fire department, the digit absorber being set to absorb only two digits before the trunk is closed, and the conversation may proceed as soon as the operator at the fire department responds.

Referring now particularly to Figs. 8 and 9, the desirable modification of the scheme for revertively controlling the cut off of the director will be explained. In this latter case, the sequence switch wiper 211', (which corresponds to the sequence switch wiper 211, Fig. 3) is arranged to ground the switching conductor 59' automatically after the transmission of the last digit when the number called contains the maximum number of digits. This avoids the necessity of providing special arrangements for switching the large number of calls which employ the maximum number of subscriber digits. On all calls employing less than the maximum number of subscriber digits, arrangements are provided

for momentarily operating the electro-polarized relay 304' (which corresponds to relay 304, Fig. 4) at the end of the transmission of the last subscriber digit. This momentary operation of relay 304' is made use of to switch the connection through and cut off the director. In the large majority of cases, the calls are completed by connector switches, such as K', and arrangements are made in this connector switch for momentarily reversing the current flow in the calling loop immediately following the termination of the last digit, thereby operating relay 304' to control the cut off of the director. However, in case a call is extended to an operator by way of a trunk accessible from selector banks, arrangements are provided in the holding circuit introduced in the trunk, the holding circuit HC, Fig. 9, for example, for momentarily reversing the current flow in the calling loop when the holding circuit is seized.

It is not thought necessary to give any particularly detailed description of the operation of the director to automatically cut it off when the maximum number of subscriber digits is used. It is thought that it will suffice to say that, upon the termination of the transmission of the fourth subscriber digit, the grounded wiper 211' is advanced in the usual manner out of engagement with the bank contact in which the fourth subscriber digit stop conductor 244' terminates into engagement with the bank contacts 601 in which the combined operating and switching conductor 59' terminates. The placing of the ground potential upon this conductor switches the connection through and causes the director to be cut off in the hereinbefore described manner.

Assuming that a number is called containing less than the maximum number of subscriber digits, and assuming that the connector K' is used in completing the connection, the registration of the complete number and the transmission of the code digits, and the subscriber digits, if any, necessary to trunk the call to the connector K' is accomplished in the usual manner, and, when the connector K' is seized, the line and release relays 125' and 126' are energized in the usual manner to prepare the switch for operation. At this point it may be stated that the connector K' is an exact duplicate of the connector K, except for the fact that the relay 611 has been added in order to take care of the momentary reversal in the calling loop following the rotary movement of the connector. Accordingly, when the first digit is transmitted to the connector K, the vertical magnet thereof operates in the usual manner and the wipers are raised opposite the desired level of bank contacts. Responsive to the transmission of the last digit to the connector K', the rotary magnet thereof is 130

operated in the usual manner and the wipers are brought into engagement with the bank contacts in which the called line terminates. Relay 130' is energized in multiple with the 5 rotary magnet and closes at armature 612 a circuit for the slow acting relay 611. Relay 611 thereupon energizes and performs the function hereinbefore described for relay 130 of the connector K at armatures 145' and 10 146', and at armature 613 prepares a circuit for the upper winding of the back bridge relay 124'.

At the end of the transmission of this last 15 digit, relay 130' deenergizes and opens the circuit of relay 611 at armature 612. Relay 611, however, being slow acting, does not deenergize immediately, and relay 130' also completes at armature 612 a circuit through armature 613 and its working contact for the 20 upper winding of the back bridge relay 124'. Relay 124' thereupon energizes and reverses conductors 121' and 123' as regards their connection with the windings of line relay 125'. When this occurs, the electro-polarized 25 relay 304' in the director responds by attracting its armature 605, closing a circuit from the grounded conductor 58' for relay 602. Relay 602 thereupon energizes and closes a locking circuit for itself at armature 604, and 30 at armature 603 prepares the switching circuit.

In the connector K', relay 611 deenergizes 35 after the interval for which it is adjusted and opens the circuit of the upper winding of the back bridge relay 124' at armature 613, in addition to performing its other functions at armatures 145' and 146'. Relay 124' now deenergizes and reverses the connections of conductors 121' and 123' back to normal, 40 whereupon the electro-polarized relay 304' deenergizes and completes at armature 605 a circuit through armature 603 and its working contact and over conductor 59' for the switching relay which corresponds to switching relay 27, Fig. 1. Responsive to the closure of this circuit, the said switching relay 45 operates to switch the connection through and cut off the director in the usual manner.

Referring now particularly to Fig. 9, it 50 will be explained how the director is cut off automatically when the trunk shown therein, extending from the banks of a selector switch to an operator, is seized. The talking conductors of this trunk, it will be noted, are normally reversed. Therefore, immediately 55 upon the seizure of this trunk, the electro-polarized relay 304' responds and operates relay 602 at armature 605. Also line relay 652 of the holding circuit HC is energized 60 and closes at armature 657 a circuit for release relay 653. Relay 653 thereupon energizes and places the impedance 654 across the outgoing talking conductors at armature 658 in order to signal the operator; grounds 65 the associated release trunk conductor at ar-

mature 659; and at armature 660 closes a circuit for the slow to pull up reversing relay 651. Accordingly, after the interval for which it is adjusted, relay 651 energizes and again reverses the incoming talking conductors at armatures 655 and 656, thereby compensating for the reversal just ahead of relay 651. Responsive to the energization of relay 651, relay 304' in the director deenergizes and completes at armature 605 a circuit through armature 603 and its working contact and the switching conductor 59 for the switching relay of the associated trunk circuit, whereupon the connection is switched through and the director is cut off in the 80 hereinbefore described manner.

Referring now again to Figs. 1-6, inclusive, the necessity for providing two arrangements for cutting off the director after code numbers will be explained fully. It has been 85 pointed out hereinbefore how the director is cut off at the end of the code number transmitted when the toll recording operator, who is called by way of the selector G, Fig. 2, is called. In this case, the full number of code 90 digits (3) is employed and the last set of office register bank contacts in the group used when the toll recording operator is called is used to control the cut off of the director by pulling two of the control relays half way, 95 in addition to determining the last code digit.

On code numbers which do not employ the full number of digits, a simpler scheme for cutting off the director after the transmission of the last code digit may be employed. Assuming that a number is being transmitted which contains only two code digits, the second and last code digit is transmitted with the wipers 451-454, inclusive, of the office register OR in engagement with 100 the second set of bank contacts in the group belonging to that number, and the third set of bank contacts in that group is not needed for transmitting a digit. Accordingly, the third set of bank contacts in that group 105 are cross-connected on the intermediate distributing frame IDF in such a manner as to operate relays *a*, *b*, and *c* when the wipers of the office register are advanced into engagement with this set of contacts at the end of the transmission of the second and last code digits. Accordingly, when relay 455 subsequently energizes and connects up the wipers, relays *a*, *b*, and *c* energize and place ground upon conductor 59, causing the director to be cut off in the hereinbefore described manner.

What is claimed is:

1. In a telephone system, means including a trunk line and a train of automatic switches 125 for connecting a calling and called line, a director for controlling said switches, means for connecting said director to the trunk, a cut-off control relay in said director, and means associated with one of said switches 130

for controlling said relay to disconnect said director from said trunk line independent of the operation of the final switch in said train.

2. In a telephone system, means including a trunk line and a train of automatic switches for connecting a calling and called line, a director, means for connecting said director to the trunk, means whereby said director controls the setting of said switches, a cut-off control relay in said director, and means individual to the final switch in said train for controlling said relay.

3. In a telephone system, means including a trunk line and a train of automatic switches for connecting a calling and called line, a director for controlling said switches, means for connecting said director to the trunk, a switch control circuit including a conductor of said trunk, a cut-off control relay in said director, and means associated with one of said switches for reversing the current flow in said control circuit prior to the operation of the final switch in said train to operate said relay.

25 4. In a telephone system, means including a trunk line and a train of automatic switches for connecting a calling and called line, a director for controlling said switches, means for connecting said director to the trunk, means for cutting said director off from the trunk when the connection is established, and means individual to one of said switches and operated after the switch has been set for controlling the cut-off operation.

35 5. In a telephone system, means including a trunk line and a train of automatic switches for connecting a calling and called line, a director for controlling said switches, means for connecting said director to the trunk, a switch control circuit including a conductor of said trunk line, a polar cut-off control relay in said director, and means for momentarily reversing the direction of current flow in said circuit to operate said relay.

45 6. In a telephone system, means including a trunk line and a train of automatic switches for connecting a calling and called line, a director for controlling said switches, means for connecting said director to the trunk, a switch control circuit over which said director transmits series of impulses to effect the control of said switches, a cut-off control relay in said director operated over said control circuit from one of said switches, and means responsive to the transmission of a predetermined number of series of impulses after the operation of said relay for cutting off the director from the trunk.

60 7. In a telephone system, means including a trunk line and a train of automatic switches for connecting a calling and called line, a director, means for connecting said director to the trunk, means whereby said director controls the setting of said switches, means for disconnecting the director from the

trunk after the switches have been operated and for connecting the calling line to the trunk, and means individual to one of said switches for controlling said director disconnecting and line connecting means.

70 8. In a telephone system, a train of automatic switches for connecting a calling and a called line, a director, means in said director for registering the called number, a switch control circuit, means in said director controlled by said registering means for transmitting series of impulses over said control circuit to operate said switches, means for reversing the direction of current flow in said control circuit, and means for connecting the calling line to said switch train responsive to the transmission of a definite number of series of impulses following said reversal.

80 9. In a telephone system, a trunk line and a train of automatic switches for connecting a calling and a called line, a director, means for connecting said director to said trunk line, means in said director for registering the called number and for transmitting series of impulses to operate said switches, means for reversing the direction of current flow in said trunk line responsive to the extension of the connection to the final switch in said train, and means rendered effective by said reversal and responsive to the transmission of the impulses for operating the final switch to disconnect the director from the trunk line.

90 10. In a telephone system, a trunk line and a train of automatic switches for connecting a calling and a called line, a director, means for connecting said director to said trunk line, means in said director for registering the called number and for transmitting series of impulses to operate said switches, means for reversing the direction of current flow in said trunk line during the process of operating said switches, and means for disconnecting the director from the trunk line responsive to the transmission of two succeeding series of impulses.

100 11. The combination, with a train of switches and a director for controlling them, said director including a sending device, of means for dissociating said director from said switches, counting relays controlling said means, a circuit over which said relays are controlled by said device, and another relay revertively controlled from one of said switches for closing said circuit.

110 12. In a director for controlling automatic switches, an office register having wipers, means for setting the wipers of said register in accordance with the office designation of a called line, a sender controlled by said register for transmitting an office code comprising two series of impulses, and means for automatically advancing the wipers of said register between said two series of impulses.

13. In a director for controlling automatic switches, an office register having wipers, means for setting the wipers of said register in accordance with the office designation of a called line, a sender controlled by said register for transmitting an office code comprising series of impulses, and means for automatically advancing the wipers of said register after each series of impulses except the last. 10
14. In a director for controlling automatic switches, an office register having wipers, means for setting the wipers of said register in accordance with the office designation of a called line, a sender controlled by said register for transmitting an office code comprising series of impulses, means for automatically advancing said register between said two series of impulses, and means for disconnecting the wipers of said register while the same is being advanced and after the last series of impulses is transmitted. 15
15. In a director for controlling automatic switches, an office register having wipers, means for setting the wipers of said register in accordance with the office designation of a called line, a plurality of sets of contacts selected by said wipers, each set corresponding to a different digit of the office code, a sender controlled by said register for transmitting the digits of the office code, and means responsive to the transmission of a digit for advancing the wipers of said register to the set of contacts corresponding to the next digit. 20
16. In a director, an office register, a plurality of digit registers, a sender initially controlled by said office register, a sequence switch for placing said sender under the control of said digit registers successively, and means responsive to the transmission of the final digit in the office code for rendering said sequence switch initially operative. 25
17. In a director, an office register, a plurality of digit registers, a sender for transmitting an office code under control of said office register and a series of subscriber's number digits under control of said digit registers, a sequence switch for placing said sender under control of said digit registers successively, means for advancing the office register between digits of the office code, and means for advancing said sequence switch between digits of the subscriber's number. 30
18. In a director, a sender including a counting switch, a set of permutational relays for controlling said switch, and means including an office register responsive to the reception of a single office designation for setting and resetting said relays. 35
19. In a director, a sender including a counting switch, a set of permutational relays for controlling said switch, means including an office register for setting said relays according to the first digit of an office code, and means for advancing said register to reset said relays according to the next digit of the code. 40
20. In a director, a sender including a counting switch, a set of permutational relays for controlling said switch, a plurality of circuit combinations for setting and resetting said relays, an office register for selecting a plurality of said circuit combinations successively and associating the same with said relays, and means for maintaining said register off normal throughout the entire selecting period. 45
21. In a director, a sender including a counting switch, a set of permutational relays for controlling said switch, a plurality of circuit combinations for setting and resetting said relays, an office register for selecting a plurality of said circuit combinations successively and associating the same with said relays, means for maintaining said register off normal throughout the entire selecting period, and a distributing frame for facilitating changes in said circuit combinations. 50
22. In a director, a sender including a counting switch, a set of relays controlling said switch, a distributing frame comprising a plurality of sets of contacts and means by which any desired contacts of each set are connected to the grounded pole of the central office battery, and means operated for associating said relays with a plurality of contact sets successively before said associated means is returned to normal position. 55
23. In a director, a sender including a counting switch, a set of relays controlling said switch, a distributing frame comprising a plurality of sets of contacts and means by which any desired contacts of each set are connected uninterruptedly to a source of potential, and means for associating said relays with a plurality of contact sets successively. 60
24. In a director, a sender including a counting switch, a set of relays controlling said switch, a distributing frame comprising a plurality of sets of contacts and means by which any desired contacts of each set are connected to a source of potential, an office register for associating said relays with a set of said contacts corresponding to the first digit in an office code, and means for advancing said register after the first digit is transmitted by the sender to associate said relays with the contact set corresponding to the next digit of the code. 65
25. In a telephone system, automatic switches for extending connections from calling lines in one office to called lines in other offices, directors in the first office, an office register for each director, a distributing frame common to all said registers, and a sender in each director controlled by the associated office register by means of said frame for controlling the setting of said switches. 70

26. In a telephone system, automatic switches for extending connections from calling lines in one office to called lines in other offices, directors in the first office for controlling said switches, an office register for each director, sets of bank contacts for said registers multiplied together, and a distributing frame having sets of contacts on one side thereof connected in multiple with the banks of said registers. 10
27. In a telephone system, automatic switches for extending connections from calling lines in one office to called lines in other offices, directors in the first office for controlling said switches, an office register for each director, sets of bank contacts for said registers multiplied together, a distributing frame having sets of contacts on one side thereof connected in multiple with the banks of said registers, a bus-bar on the other side of said frame permanently connected to a source of potential, and temporary jumpers connecting one or more contacts of each set on said frame with said bus-bar. 15
28. In a telephone system, automatic switches for extending connections from calling lines in one office to called lines in other offices, directors in the first office for controlling said switches, an office register for each director, said registers being supported adjacent one another in rows, a common distributing frame, and multiple connections between the banks of said registers and one side of said frame. 25
29. In combination, a director including a sender for controlling automatic switches, a distributing frame common to said director and other similar directors, a plurality of circuit conductors terminating in said frame, means including an office register for selecting a plurality of said conductors simultaneously, means for completing a circuit over one of the selected conductors to control said sender to transmit a digit, and means for then closing circuits over the other selected conductors in succession to control the sender to transmit other digits. 35
30. The combination, with a plurality of directors, of a distributing frame common to said directors, sending apparatus in each director, means including an office register for preparing a plurality of circuits each including connections on said frame, means for utilizing said circuits for controlling said sender to transmit a plurality of digits and means for selecting a new circuit for use after each digit is transmitted. 50
31. In a director, an office register, means for setting said register in accordance with an office designation, means controlled by said register for transmitting a digit in the office code concerned, and means for automatically resetting said register responsive to the operation of said transmitting means. 65
32. In a director, an office register, means for setting said register in accordance with an office designation, means controlled by said register for transmitting a digit in the office code concerned, means for automatically resetting said register after the digit is transmitted, and means for causing the said transmitting means to transmit a second digit in the code in accordance with the new setting of said register. 70
33. In a director, an office register having a plurality of set positions corresponding, respectively, to the several digits in an office code, other set positions corresponding to other codes, means for setting said register in one of said positions depending on the code to be used, means for transmitting said digits under control of said register, and means for changing the position of said register after each digit is transmitted. 75
34. In a telephone system, means including a trunk line and a train of automatic switches for connecting a calling and called line, a director for controlling said switches, means for connecting said director to the trunk, means including counting means for counting the series of impulses transmitted by said director and for disconnecting said director from the trunk when a predetermined number of series of impulses have been counted, and means for delaying the action of said counting means until a switch of a given numerical order has been reached. 80
35. In a telephone system, means including a trunk line and a train of automatic switches for connecting a calling and called line, a director for transmitting series of impulses to control said switches, means for connecting said director to the trunk, means including counting means controlled by said impulses for disconnecting said director from the trunk, and means for delaying the operation of said counting means until only a predetermined number of series of impulses remain to be transmitted. 85
36. In a telephone system, means including a trunk line and a train of automatic switches for connecting a calling and a called line, a director for transmitting series of impulses to control said switches, means for connecting said director to the trunk, means including counting means controlled by said impulses for disconnecting said director from the trunk, and means controlled from said train of switches for delaying the operation of said counting means until only a predetermined number of series of impulses remain to be transmitted. 90
37. In a telephone system, means including a trunk line and a train of automatic switches for connecting a calling and called line, a director including an impulse sender for controlling said switches, counting means in said director, and means responsive to the extension of a connection to a switch of a fixed numerical order other than the first numerical 105

switch in said train for initiating the operation of said counting means.

38. In a telephone system, means including a trunk line and a train of automatic switches for connecting a calling and called line, a director for controlling said switches, means for connecting said director to the trunk, means controlled by the operation of said director in controlling said switches for disconnecting the director from the trunk after the final switch has been set, and means for initiating the operation of said disconnecting means after the operation of the switch preceding the final switch and before the operation of the final switch.

39. In a telephone system, means including a trunk line and a train of automatic switches for connecting a calling and called line, a director for controlling said switches, means for connecting said director to the trunk, means for disconnecting said director from the trunk, means in the final switch of said train for testing the called line to determine its busy or idle condition, and means in only the final one of said switches and independent of any line-testing means for controlling the operation of said director disconnecting means.

40. In a telephone system, means including a trunk line and a train of automatic switches for connecting a calling and called line, a director for controlling said switches, means for connecting said director to the trunk, means for disconnecting said director from the trunk, and means in said final switch operated momentarily after the final switch has been set to control said director disconnecting means.

41. In a telephone system, means including a trunk line and a train of automatic switches for connecting a calling and called line, a director for controlling said switches, means for connecting said director to the trunk, means for disconnecting said director from the trunk, means in the final switch for twice reversing the current flow in the portion of the connection between said trunk line and said final switch after the final switch has been set, and means responsive to the second reversal for operating said director disconnecting means.

42. In a telephone system, means including a trunk line and a train of automatic switches for connecting a calling and called line, a director for controlling said switches, means for connecting said director to the trunk, means for disconnecting said director from the trunk, means for reversing the current flow in the portion of the connection extending ahead from said trunk line, means for again reversing the current flow in such portion after the final switch is set, and means responsive to the second reversal for operating said director disconnecting means.

43. In a telephone system, a trunk line di-

vided into two sections, a train of automatic switches controlled over the second section of said trunk line to extend a connection to a called line, a director for controlling said switches, means for extending a connection from a calling line to the first section of said trunk line and for connecting said director to the second section, a polarized relay associated with the first section of said trunk lines, means for reversing the current flow over the second section of said trunk line, means responsive to such reversal for disconnecting said director from the second section of the trunk line and for joining the two sections together, and means for preventing said polarized relay from responding to such reversal.

44. In a director, an office register, means for setting said register in accordance with an office designation, means controlled by said register for transmitting a digit in the office code concerned, and means automatically effective after the digit is transmitted for producing a fixed and invariable change in the setting of said register.

45. In a director, an office register, means for setting said register in accordance with an office designation, means controlled by said register for transmitting a digit in the office code concerned, and means automatically effective after the digit is transmitted for resetting said register in a predetermined new position.

46. In a director, an office register, means for setting said register in accordance with an office designation, means controlled by said register for transmitting a plurality of digits in the office code concerned, and means automatically effective after the transmission of each digit for each time resetting said register in a predetermined new position.

47. In a director, an office register, means outside of said director for setting said register in accordance with an office designation, means controlled by said register for transmitting a digit in the office code concerned, and means in said director for automatically resetting said register after the digit is transmitted.

48. In a telephone system, a director, means for seizing said director, an office register in said director, means for setting said office register in accordance with an office designation, means controlled by said register for transmitting a digit in the office code concerned, and means for thereafter automatically resetting said register while maintaining the director seized.

49. In a telephone system, a director, means for seizing said director, an office register in said director, means for setting said office register in accordance with an office designation, means controlled by said register for transmitting digits in the office code concerned, and means for thereafter automatically

cally resetting said register a plurality of times while maintaining said director seized.

50. In a telephone system, means including a trunk line and a train of automatic switches for connecting a calling and a called line, means including said trunk line and a second train of automatic switches for connecting a calling line to a second called line, said second train of automatic switches containing a smaller number of switches than the first train, a director for controlling said switches, means for connecting said director to the trunk, means for disconnecting said director from the trunk, means in said director effecting after the last switch in the first named train has been set to operate said disconnecting means, and means controlled from the second train of switches for operating said disconnecting means independent of the operation of said means in the director.

51. In a telephone system, a trunk line, means for extending a connection from a calling line to said trunk line, automatic switches for extending said connection to any one of a plurality of called lines, the number of switches required depending upon the line called, a director for controlling said switches, means in said director effective when the maximum number of switches are required to extend a connection to a called line for disconnecting said director from the trunk line, and means revertively controlled from one of the switches involved when a lesser number of switches is used in completing a connection for operating said cut-off means.

52. In a telephone system, automatic switches for extending connections from calling lines in one office to called lines in other offices, directors in the first office for controlling said switches, an office register for each director, said registers being assembled in a group apart from said directors, a common distributing frame, and multiple connections between the banks of said registers and one side of said frame.

53. In a telephone system, automatic switches for extending connections from calling lines in one office to called lines in other offices, directors in the first office for controlling said switches, an office register for each director, said registers being assembled in a group apart from said directors, and multiple connections between the banks of said registers.

54. In a telephone system, means including a trunk line and a train of automatic switches for connecting a calling and a called line, a director including an impulse sender for controlling said switches, counting means in said director, and means responsive to the extension of a connection to a switch of a fixed numerical order other than the first numerical switch in said train for initiating the operation of said counting means to count series of impulses.

55. In a telephone system, means including a trunk line and a train of automatic switches for connecting a calling and a called line, a director for controlling said switches, means for connecting said director to said trunk, counting means in said director, means responsive to the extension of a connection to a switch of a fixed numerical order other than the first numerical switch in said train for initiating the operation of said counting means to count series of impulses, and means controlled by said counting means when fully operated to disconnect said director from said trunk.

56. In a director, an office register, means for setting said register in accordance with an office designation, means controlled by said register for transmitting a digit in the office code concerned, a plurality of second setting positions, and means for automatically resetting said register in one of said second positions, said second position being determined by or dependent upon the first setting of said register.

57. In a director, an office register, a plurality of setting positions, each said position corresponding to the first digit in an office code, means for setting said register in one of said positions, means controlled by said register for transmitting the digit corresponding to said selected position, a plurality of second setting positions, and means for automatically setting said register in the second setting position corresponding to the second digit of the selected office code.

58. The combination, with a train of numerical switches and a director for controlling them, said director including a sending device, of means for disassociating said director from said switches, counting relays controlling said means, a circuit over which said relays are controlled by said device, and means controlled by an intermediate one of said numerical switches for closing said circuit.

59. The combination, with a train of numerical switches and a director for controlling them, said director including a sending device for transmitting the digits of the office code and the subscriber's digits, the subscribers' digits comprising all of the digits exclusive of the office code, of a counting means for counting only the number of subscribers' digits transmitted.

60. The combination, with a train of numerical switches and a director for controlling them, said director including a sending device for transmitting the digits of the office code and the subscribers' digits, the subscribers' digits comprising all of the digits exclusive of the office code, of a counting means for counting only the number of subscribers' digits transmitted, and a second counting means effective when a connection has been extended to an intermediate one of

said numerical switches by the transmission of certain subscribers' digits to count the remaining subscribers' digits.

61. In a telephone system, automatic switches for extending connections from calling lines in one office to called lines in other offices, directors in the first office for controlling said switches, office registers for said directors, said registers being assembled in a

10 group apart from said directors, a common distributing frame, and multiple connections between the banks of said registers and one side of said frame.

62. In a telephone system, a train of automatic switches, an impulse sending device for generating and transmitting impulses for controlling the setting of said switches, means for associating said device with said switch train, counting relays, and means controlled by said sending device for operating said counting relays to disconnect said sending device from said switch train.

63. In a telephone system, a train of automatic switches, an impulse sending device for generating and transmitting impulses for controlling the setting of said switches, means for associating said device with said switch train, counting relays, means controlled from one of the switches in said train of switches for connecting said device with said counting relays, and means controlled by said device for operating said counting relays to disconnect said device from the switch train.

64. In a telephone system, a plurality of trains of switches, a register sender, means for appropriating said sender for use and for operating it to control the switches of any one of said trains successively, and means in the last switch of each of said trains effective upon the completion of its operation for placing a condition on its incoming conductors distinct from any condition placed on the incoming conductors of any other switch in the train, and means for thereupon freeing said sender responsive to said condition.

65. In a telephone system wherein a train of automatic switches is to be operated over a trunk line by a register sender, means for associating a register sender with said trunk line, said sender being effective to operate the switches of said train successively, the last switch of said train being arranged so that upon its operation by the sender it places a condition on its incoming conductors different from any condition placed on the incoming conductors of any of the preceding switches of the train, and means responsive to said condition for thereupon freeing said sender.

66. In a telephone system wherein a train of automatic switches is to be operated over a line, a register sender, means for connecting said sender to said line, said sender being

operable to successively operate the switches of said train over said line, means responsive to the completion of the operation of one of the switches in said train for placing a condition on its incoming conductors different from the condition placed on the incoming conductors of any preceding switch, and means responsive to said condition for thereupon freeing said sender.

67. In a telephone system, a plurality of automatic switches, a register sender arranged to be taken for use to successively operate certain ones of said automatic switches to connect them in a train of indefinite length, said switches being divided into two classes, any switch of one class being arranged so that upon the completion of its operation it places a condition on its incoming conductors different from any condition placed on the incoming conductors of any switch of the other class, and means responsive to said condition being placed on the incoming conductors of a switch of the said one class after a connection has been extended to said switch and the switch has been operated for thereupon freeing said sender.

68. In a telephone system wherein automatic switches may be operated to link extensions from calling lines, said switches being in two classes, one class composed of intermediate switches and the other class composed of final switches, a register sender, means for taking said register sender for use to link an extension from a calling line, said sender being operable to operate an indefinite number of said intermediate switches to link an extension to a final switch and to operate the final switch, and means effective automatically responsive to the completion of the operation of the final switch and independent of the number of intermediate switches connected in the train for thereupon freeing said sender.

69. In a telephone system wherein automatic switches are operated under the control of register senders to link extensions from calling lines, means for taking a register sender for use and for setting up any one of a plurality of number registrations differing in that certain ones have added digits not contained in other numbers, sending apparatus in the seized register sender for operating said switches to link an extension in accordance with any registered number, and means controlled from a linked extension for automatically freeing the register sender upon the operation of the last switch used to link an extension.

70. In a telephone system wherein automatic switches are operated to link extensions from calling lines by register senders which are in turn set over the calling lines, means for appropriating a register sender for use in linking an extension from a calling line, sending apparatus in the register sender for

70

130

transmitting series of impulses to effect the control of the automatic switches in accordance with the setting of the register sender, and means controlled from a linked extension 5 for automatically freeing said register sender.

71. In a telephone system wherein automatic switches are operated to link extensions from calling lines by register senders which in turn are set over the calling lines, means for 10 appropriating a register sender for use in making an extension from a calling line, sending apparatus in the register sender for transmitting series of impulses to effect the control of the automatic switches in accordance 15 with the setting of the register sender, means in the switch used to link the final extension for placing a condition on the incoming conductors thereof different from any condition placed on the incoming conductors of preceding switches, and means responsive to said condition for freeing the register sender.

72. In a telephone system wherein connections are set up from calling lines by automatic switches by way of intermediate lines 25 to called lines under the control of register senders which are in turn set over the calling lines, means for taking a register sender for use to link an extension from a calling line, and means controlled over the linked extensions and automatically responsive to the linking of the extension to a called line for 30 freeing the register sender regardless of the number of intermediate lines through which the extension is linked.

73. In a telephone system, a line, means for seizing said line, and means automatically responsive to said seizure for transposing said line.

74. In a telephone system, a line having two 40 conductors and an individual battery-feed bridge, means for seizing said line, and means automatically responsive thereto for transposing the conductor of said line with respect to said bridge.

75. In a telephone system, a line, means for 45 setting up a current flow over said line and for periodically interrupting said flow, a second line having an individual battery-feed bridge, automatic switching apparatus responsive to 50 said periodic interruptions to extend the first line to the second line so that the current thereafter flowing over the first line is received from the second line through its battery-feed bridge, the connection between the 55 two lines being so made however that the current flows in the opposite direction in the first line, and means automatically responsive to the connection being made for transposing the second line with respect to its battery-feed bridge so that the current flow in the 60 first line is reversed back to its initial direction.

76. In an automatic telephone system, a 65 register sender, step-by-step switches controlled thereby, an impulse sender, a trans-

lating switch included in said register sender, means to position said translating switch in accordance with a number of sets of impulses produced by the impulse sender, and means common to said register sender and to a plurality of other register senders for causing said register sender to transmit a different number of different sets of impulses to said step-by-step switches in accordance with the setting of said translating switch. 70

77. In an automatic telephone system, a register sender, step-by-step switches controlled thereby, an impulse sender, a translating switch included in said register sender, means to position said translating switch under the control of said impulse sender, and means common to said register sender and to a plurality of similar register senders for causing the said register sender to transmit a greater or less number of sets of impulses 80 to said step-by-step switches in accordance with the setting of said translating switch. 85

78. In a call director, an office register having a plurality of different settings, each corresponding to a different office, sending means 90 associated with said register, means for operating said sending means under the control of said register in any one of its several positions to transmit a plurality of series of impulses, means common to said office 95 register and to a plurality of similar office registers whereby the value of the series of impulses corresponding to any particular position of said register may be readily changed, and automatic switching mechanism responsive to said impulses to extend a telephone connection. 100

79. In a telephone system, a plurality of register senders, a plurality of conductors multiplied into a register in each of said register senders, means for setting said registers over subscribers' lines onto said conductors to predetermine digits, and means for operating the sending portion of said register senders simultaneously each in accordance with the 105 setting of the associated register and without interference between the different senders. 110

80. In a register sender system, a plurality of register senders, a plurality of conductors multiplied into a register in each of said register senders, means for setting said registers over subscribers' lines onto said conductors to predetermine digits, means for operating the sending portion of said register senders simultaneously each in accordance with the 115 setting of the associated register and without interference between the different senders, a distributing frame, said conductors being connected to one side of said distributing frame, terminals on the other side of said frame, and facilities for interconnecting the terminals on the other side of the frame with the terminals to which the said conductors are connected. 120

81. In a register sender system, a plurality 125

of registers, impulse senders arranged to send trains of impulses in accordance with the settings of the said registers, automatic switching apparatus responsive to said trains 5 of impulses to simultaneously set up telephone connections, a plurality of common conductors determining the values of respective settings of all of said registers, and a distributing frame including readily changeable jumpers for simultaneously varying the 10 value of a given setting of all of said registers.

82. In a register sender system for use in a telephone system in transmitting trains of impulses to automatic switching apparatus 15 to effect the operation thereof, a plurality of register senders each including office registering apparatus for registering office designations, sending apparatus arranged to be controlled in accordance with the office designations registered to send out the trains of 20 impulses, and a translating device comprising jumpers and a terminal set for each called office, said jumpers and terminal sets being common to all of said register senders.

83. In combination, a distributing frame, sets of control conductors connected to said frame, an office register operated directly responsive to digits dialled by a calling subscriber to select a set of said conductors, an 30 impulse sender, and means operated from said frame over the selected set of conductors for controlling said sender.

84. In a director, a sender, a storage device for controlling said sender, a step-by-step 35 office register having wipers connected to said device, bank contact sets selectable by said wipers, and a cross connecting rack to which said contact sets are connected.

85. In a register sender system, an office 40 register, a distributing frame associated with the banks of said register, a sender associated with the wipers of said register, and means for controlling said sender from said frame through said banks and wipers while the 45 register is in set position.

86. In a director, a sender, a relay storage device and a plurality of register switches

for successively controlling said sender, sets of control conductors for setting said storage device, and an office register directly responsive to a subscriber's dial for connecting any one of said sets to said device. 50

87. In a telephone system, automatic switches for extending connections from calling lines in one office to called lines in other offices, directors in the first office for controlling said switches, office registers for said directors, said registers being assembled in a group apart from said directors, a common distributing frame, and multiple connections between the banks of said registers and one side of said frame. 55

88. In combination, a plurality of groups of conductors each corresponding to a predetermined control to be exercised, a switch controller, means for selecting a plurality of groups of said conductors in accordance with a portion of a telephone number, means for successively associating said controller with said groups, and means effective each time said controller is associated with a group of conductors and controlled over the group for operating the controller to exercise the predetermined control. 60

89. In a director, a storage device, means 75 for setting said device, means controlled by said device for transmitting a digit, and means for automatically resetting said device responsive to the operation of said transmitting means. 70

90. In a director, a decoder, a sender controlled by said decoder, and means for operating the decoder and sender alternately to transmit a plurality of digits. 80

91. In a director, an office register, a decoder, means for transmitting digit indications through the wipers of said register to said decoder, a sender controlled by said decoder, and means for operating the sender to transmit each decoded digit before the 90 next digit is decoded. 85

RODNEY G. RICHARDSON.
JOHN I. BELLAMY.
